CLAIM

The ornamental design for a paper clip or similar article, as shown and described.

DESCRIPTION

FIG. 1 is a front elevational view of a paper clip or similar article showing my new design;

FIG. 2 is a right side elevational view;

FIG. 3 is a rear elevational view;

FIG. 4 is a left side elevational view;

FIG. 5 is a top plan view; and

FIG. 6 is a bottom plan view thereof;

FIG. 7 is a perspective view showing a second embodiment of my new design; and

FIG. 8 is a side elevational view thereof.

FIG. 1.

FIG. 2.

FIG. 3.

FIG. 4.

FIG. 5.

FIG. 7.

FIG. 6.

FIG. 8.
